UNITED STATES PATENT OFFICE.

HARRY ELMER BICKNELL, OF NIAGARA FALLS, ONTARIO, CANADA.

PAPER-CLASP.

1,163,127.

Specification of Letters Patent.

Patented Dec. 7, 1915.

Application filed January 11, 1913. Serial No. 741,541.

To all whom it may concern:

Be it known that I, HARRY ELMER BICKNELL, a citizen of the United States, residing at Niagara Falls, in the Province of Ontario and Dominion of Canada, have invented new and useful Improvements in Paper-Clasps, of which the following is a specification.

The present invention relates broadly to 10 the class of paper clasps and more particularly to that class of such devices which are formed from a single sheet of material.

An object of my invention is as above set forth, to provide an improved paper 15 clasp constructed from a single sheet of material, thus reducing its cost of manufacture to a minimum.

Another object of my invention is to provide a paper clasp wherein means are employed for insertion in the paper, means also being devised for obviating the accidental dislodgment of the other means, thus adding to the efficiency of the device.

A further object of my invention is to 25 provide a paper clasp which is readily applicable to sheets of paper of different thicknesses, its attachment thereto being obviously facilitated through the medium of a tapering tongue.

30 A still further object of my invention relates in the provision of a device of the above-mentioned character of such construction as to render the same cheap in manufacture, and easy to bend into shape.

35 With the above and other objects in view, my invention relates to such details of construction and in the arrangement and combination of the several parts as will be hereinafter fully described and specifically 40 pointed out in the appended claims.

In describing my invention in detail, reference will be had to the accompanying drawings wherein like characters denote like or corresponding parts throughout the several views, and in which:—

Figure 1 is a plan view of the blank form of clasp. Fig. 2 is a side elevation of the clasp illustrating the same in a locked position. Fig. 3 is a side elevation of the clasp 50 showing the manner in which the paper is engaged thereby, and Fig. 4 is a perspective view of the clasp.

In the accompanying drawings, wherein is illustrated the preferred form of my invention, the numeral 10 designates the body

portion of the clasp which is preferably formed of sheet metal or the like material. A constricted portion 11 is provided upon the body portion which extends therefrom at one end and is adapted to be bent over the 60 same to extend in parallel relation therewith as shown in Fig. 2. The other end of the body is provided with a similar constricted portion 12 which is enlarged at its forward end to form a member 13 of similar size and shape to the body portion the member 13, because of its configuration and relation to the body portion 10, provides a grip for the finger nail when it is desired to disengage the device from a manuscript. Here it will 65 be recognized that the entire device can be stamped from a single sheet of metal, with one impression of the cutting die thus greatly reducing the cost of devices of this nature.

A substantially V-shaped portion 14 is stamped from the member 13, in the manner clearly illustrated in Fig. 1, the smaller portion of this tongue depending from the member after the latter has been bent into 80 the position shown in Fig. 3, and in such a manner that when the member 13 is depressed, the same will be readily inserted through the sheets of paper. After the tongue is inserted through the sheets of paper, it contacts the upper face of the body portion whereupon it is bent to extend parallel with the constricted portion 11, and to spring upwardly because of its nature of metal into close proximity with the portion 90 11, thus obviating its accidental removal.

Attention is particularly called to the specific construction of the tongue 14. The tongue mentioned is constricted at its connection with the body portion of the device 95 thus providing a thin portion which greatly facilitates the bending of the tongue and also provides suitable shoulders thereon which prevent its accidental withdrawal from the sheets of paper after once being 100 inserted therethrough.

From the foregoing it is thought that the operation, advantages and novel features of this invention will be readily comprehended.

I desire to lay the greatest of stress upon 105 the simplicity of the device, inasmuch as the cost of devices of this nature is greatly reduced by its provision.

Such changes as are permissible by the subjoined claims may be resorted to, with- 110

out departing from the spirit of my invention.

Having thus fully described my invention, what I claim as new and desire to secure by 5 Letters Patent is:—

1. A paper clasp including a body portion, a constricted portion formed on one end of said body portion adapted to fold over said body portion and lie in parallel 10 relation thereto, a second constricted portion formed on the opposite end of said body, an enlargement formed on said last mentioned constricted portion, said enlargement adapted to fold over in close proximity to said 15 body and to lie in slightly spaced relation to a clasped manuscript to provide a finger grip to disengage the clasp from a manuscript, a tongue struck from said enlargement, said tongue adapted to bend and pierce the paper and extend under the end 20 of said first constricted portion to retain

sheets of paper within the clasp for the purpose set forth.

2. A device as specified, including a body having a constricted portion intermediate its ends forming a pair of enlarged portions, said enlarged portions folded upon each other into parallel spaced relation, one of said enlarged portions having a tongue extending from its outer end and bent into 25 parallel relation therewith, and a sharpened edge tongue struck from the other of said enlarged portions adjacent an end thereof, said sharpened tongue being engageable through an object and under the end of the 30 first mentioned tongue whereby to retain said objects between said enlarged portions. 35

HARRY ELMER BICKNELL.
